UNITED STATES PATENT OFFICE

2,003,399

DOOR OPERATOR

Joseph C. Tamsitt, Aurora, Ill., assignor to Rich-
ards-Wilcox Manufacturing Company, Aurora,
Ill., a corporation of Illinois

Application May 2, 1932, Serial No. 608,661

19 Claims. (Cl. 187—52)

This invention relates to door operators. Modern elevators frequently use a mechanism for automatically opening the hatchway doors when the elevator is stopped at a floor level, and for closing these doors prior to the restarting of the elevator away from that floor. My present invention provides a new and improved device for accomplishing this purpose, a device which is light in weight and therefore reduces the deadweight load that must be carried by the elevator. My invention also provides for a rapid opening and closing of the elevator door in a quiet and safe manner which includes checking its movement at the ends of its path of travel, and further provides for the instantaneous release of the door mechanism from the opening mechanism in case the door strikes an obstruction, thereby eliminating the possibility of a passenger being pinned between the door and doorframe.

In the preferred embodiment of my invention, a stationary rail is mounted upon the elevator in a convenient location, such as for example at the top of the cab. This rail carries a power driven carriage to which is pivoted a shoe or operating rod which is adapted to engage the latching mechanism of the doors in the hatchway. Normally the shoe is in such a position with respect to the latches that the car may be raised and lowered in the shaft without engaging the latches that it passes.

When it is desired to stop the elevator at a particular floor and open the hatchway doors at that floor, a control lever is operated to bring a range relay into its operating position. When the floor is approached a stationary cam in the hatchway engages with the range relay to render the door operator operative when the elevator has been brought to rest. As soon as the elevator stops the door operator mechanism is started and the carriage and shoe are moved into such a position that the shoe engages the latching mechanism of the door and operates it first to unlatch the door and then to move the door to its open position.

The initial movement of the carriage may be checked by a checking device, either mechanically or electrically, so that it is brought up to its full speed gradually and the shoe is therefore brought into engagement with the latching mechanism and the movement of the door started without abruptness and the operation therefore is quiet and safe.

As the door approaches its open position a mechanical checking device is engaged by the carriage and the door and carriage are gradually

brought to rest. The door operator is stopped by a limit switch when it is in such position that the door is fully open. The door remains opened until further operation by the elevator operator at which time the carriage is moved in the opposite direction, and as before the first part of its movement may be checked so that the door and carriage are started gradually and without shock. The final movement of the door into its closed position is checked by a checking device and the door operator is stopped by a limit switch.

The door operator of my invention is adapted to be connected to the gate or door of the elevator cab, and to operate that gate simultaneously with an operation of the hatchway doors. Preferably this connection includes a safety release which quickly detaches the cab gate from the carriage of the operator when the gate strikes a passenger, or any obstruction which prevents its free movement.

My invention also includes the provision of an interlocking arrangement whereby movement of the elevator car away from the floor level is impossible until the hatchway door has been completely closed and latched. This prevents the possibility of hatchway doors being left open when the elevator is elsewhere in the shaft.

My invention will be best understood by reference to the accompanying drawings in which a preferred embodiment of it is shown by way of example, and in which:

Figure 1 is an elevational view of the operator mechanism located at the top of the elevator;

Figure 2 is an end view of the mechanism shown in Figure 1;

Figure 3 is a diagram illustrating the operation of the door checking mechanism;

Figure 4 is a cross sectional view taken along a vertical plane through the longitudinal axis of the door check mechanism;

Figure 5 is a cross sectional view of the door check mechanism taken along a horizontal plane through the axis of the mechanism;

Figure 6 is a fragmentary cross sectional view of the valving arrangement of the door check mechanism taken substantially along the line 6—6 of Figure 5 looking in the direction of the arrows;

Figure 7 is a plan view of the door latch mechanism showing the operating shoe engaged with it;

Figure 8 is a plan view of the door latch mechanism showing the operating mechanism in its normal position;

- Figure 9 is an elevational view of the door latch;

- Figure 15 is an elevational view showing the connection between the door operating mechanism and the cab gate of the elevator;
- Figure 16 is a cross sectional view taken along the line 16—16 of Figure 15 looking in the direction of the arrows;
- Figure 17 is a plan view of a limit switch mechanism;
- Figure 18 is a cross sectional view through the limit switch taken along the line 18—18 of Figure 17 looking in the direction of the arrows;
- Figure 19 is an elevational view of the interlocking contacts of the device;
- Figure 20 is a schematic circuit diagram showing how the devices of my invention may be connected together electrically;
- Figure 21 is a plan view of a modified form of operator;
- Figure 22 is an end elevational view of the operator shown in Figure 21;
- Figure 23 is a front elevational view of the operator shown in Figures 21 and 22;
- Figure 24 is an end elevational view of a modified form of latch and interlocking device applied to a hatchway door;
- Figure 25 is a front elevational view of the latch and interlocking device shown in Figure 24;
- Figure 26 is a plan view of the latch and interlocking device shown in Figure 24 drawn to an enlarged scale and showing also a modified form of latch operating shoe carried by the operator carriage, with the shoe in its normal position;
- Figure 27 is a view similar to Figure 26, showing the latch and shoe in their respective operated positions;
- Figure 28 is a cross sectional view of a simplified carriage checking device;
- Figure 29 is a fragmentary view taken along the line 29—29 of Figure 28 looking in the direction of the arrows;
- Figure 30 is a fragmentary view taken along the line 30—30 of Figure 28 looking in the direction of the arrows;
- Figure 31 is an elevational view of a modified form of cab gate operating device; and
- Figure 32 is a plan view of the device shown in Figure 31.
- Referring now to the drawings in more detail, particularly Figures 1 and 2, it will be seen that the door operating mechanism indicated generally at 1 is mounted on the top front edge of the cab 2 of the elevator, that is adjacent to the doors that are to be operated by it.
- This door operating mechanism consists of a suitable frame work 3 attached to the frame of the elevator 2 in any preferred manner. Obviously the specific details of the frame 3 and its manner of attachment to the elevator will vary with the particular conditions met, and the specific arrangement shown by way of example therefore need not be explained in any great detail.
- Mounted upon this framework is a rail or guide 4 which is made adjustable with respect thereto by adjusting screws 5 and nuts 6 to permit a limited movement of the rail longitudinally.
- Mounted upon this rail is a carriage 7 to which is pivoted an operating shoe 8. This shoe is urged to rotate about its pivot 9 by springs 11, 10 which are disposed in a recess formed in the carriage 7, and have one end engaging the bottom wall of the recess and their other end engaging the shoe 8. A stop member 10, suitably secured to the carriage 7, extends upwardly in front of the shoe 8. The springs 11 serve to urge the shoe 8 forwardly about its pivot 9, as shown in Figure 8, and the stop member 10, abutting the forward edge of the shoe, limits such forward movement of the shoe. The purpose of the pivotal connection of the operating shoe will be hereinafter explained. The top and bottom edges of the shoe 8 are bent inwardly toward the car as indicated at 12 for a purpose which will be hereinafter explained. The carriage 7, shoe 8, rail 4, and in fact the entire framework 3, may be conveniently made of iron or steel. If desired, bearing blocks 13 may be interposed between the framework of the carriage 7 and the guide rail 4 to permit frictionless movement of the carriage upon this rail.
- Mounted upon the framework 3 are a pair of sprocket wheels 14 and 15 to one of which is connected a gear reduction mechanism 16 by means of a suitable coupling member 17, Figure 2. This mechanism, indicated generally at 16, may be a series of spur gears or if desired a worm and gear speed reducing mechanism of any preferred type. A motor 18 connected to the speed reducing mechanism 16 drives that mechanism and in turn rotates the sprocket wheels 14 and 15. A suitable chain 19 is attached at its opposite ends 20 to the carriage 7 by means of an adjustable connection indicated generally at 21 and preferably comprising a bolt attached to the end of the chain and projecting through a member on the carriage and nuts threaded upon the projecting end of the bolt. Obviously any other preferred arrangement for attaching and tightening the chain 19 may be provided within the teachings of my invention. The chain 19 is threaded over the sprocket wheels as shown.
- The carriage 7 is moved by the motor 18 through its rotation of the sprocket wheels 14 and 15 in the obvious manner. A lubricating means 22 may be provided to lubricate the rail 4 so that the carriage 7 may be moved over it quickly and quietly.
- Mounted upon the frame 3 are checking devices 25 and 26, which operate to retard the movement of the carriage 7 as it approaches its limit positions.
- As will be seen in Figures 1, 3, 4, 5 and 6, the retard devices 25 and 26 comprise a shaft 27 journaled for oscillation about a substantially horizontal axis. Mounted upon this shaft is an arm 28 the lower end of which extends down into the path of rollers 29 and 30 carried by a plate 31 on the cab side of the carriage 7. The opposite end of the arm 28 contains a counterweight 32.
- As the carriage 7 moves to the left, Figure 3, the roller 29 engages the upper surface of the arm 28 and rotates that arm in a clockwise direction about the axis of its shaft 27 into the position shown in the dotted line. When the carriage 75

7 moves in the opposite direction, the roller 30 engages the opposite side of the arm 28 and rotates that arm in a counterclockwise direction about the axis of its shaft 27. When the arm is in either one of its limit positions the counterweight 32 is past center and therefore tends to rotate the arm further in the direction in which it was moved to reach that limit position. This insures that the arm will remain in place when it is in either of its limit positions.

The shaft 27 is journaled into the body 33 of the checking mechanism, and a bell crank 34 is rigidly attached to the end of that shaft within the mechanism. A cylinder 35 is also located in the body 33 of the mechanism, that cylinder being closed by a suitable plug 36 and sealed by a gasket 37. Located within the cylinder 35 is a piston 38 which comprises two sections 39 and 40 located upon its opposite ends. Carried within the piston 38 and engaging the end of the bell crank 34 is a pusher plate 41 which fits within a recess 42 in the piston and is held against the bell crank 34 by a spring 43. The opposite end of this spring fits against the valve seat 44 which contains a ball valve 45 that is maintained upon its seat by a spring 46.

The opposite end of the piston contains a pusher plate 47 which also bears against the bell crank 34 and projects into a pocket 48 in that end of the piston. This pocket is closed by a valve 49 which is retained on its seat by a coil spring 50.

Leading out of the end 51 of the cylinder 35 is a by-pass passage 52 which is normally closed by a valve mechanism 53 held on its seat by a spring 54. The tension of this spring is adjusted by a stud screw 55 threaded into the plug 56 by which the valve chamber 57 is closed. Suitable packing means 58 prevents leakage of fluid around this stud screw 55. Leading out of the valve chamber 57 is a port 59 which communicates with a second by-pass passageway 60 that opens through a port 61 into the opposite end 62 of the cylinder 35. The by-pass passageway 60 also leads to a valve 63 which is maintained upon its seat by a spring 64, the tension of which is adjusted by a stud screw 65 threaded into the plug 66 by which the valve chamber 67 is closed. Suitable packing means 68 are similarly provided to prevent leakage of fluid around this stud screw.

The valve 63 is provided with an opening 69 into which a reduced portion 70 of the stud screw 65 projects, that projection serving also as a guide for the valve. The valve 69 contains a leakage port 69' which is partially covered by the end of the reduced portion 70 of the screw 65 to regulate the amount of leakage through this port.

The valve chamber 67 opens through port 71 into the first mentioned passageway 62.

The body 33 of the checking mechanism projects downward and contains threaded openings 73 and 74 by which it is mounted upon the framework 3 of the operating mechanism. A cavity 75 communicating with the cylinder 35 in the central portion of the piston is contained in this lower projection of the body 33.

A quantity of fluid such as light oil for example, is sealed in the checking device. As the shaft 27 is rotated in a clockwise direction, Figure 5, the bell crank 34 pushes the pusher plate 41 against the tension of spring 42 and as the motion is continued the piston 38 is moved to the right. Oil in the end section 51 of the cylinder is thus placed under pressure and forced

through the by-pass passageway 52 where it engages the valve 53. The liquid also flows through the port 71 into the valve chamber 67 and a small quantity of it leaks through the opening in the valve 69 into which the projection 70 of the stud screw 65 projects, however, since this opening is small the quantity of liquid flowing in this path is correspondingly small. Valve 69 is of course more firmly seated upon its seat by pressure built up in the valve chamber 67. A small quantity of fluid leaks out of chamber 67 through the port 69'.

The pressure in the passageway 52 overcomes the tension of spring 54 and raises the valve 53 off of its seat, permitting the oil to flow into the valve chamber 57 and out of it through the port 59 into the passageway 60 and through the port 61 into the end section 62 of the cylinder. Since the piston 38 is moving to the right the chamber 62 will be increasing in volume so that there will be ample room for the oil received by it.

When motion in the opposite direction is started bell crank 34 moves against the pusher plate 47 and moves that plate into the chamber 48 against the pressure of oil contained in that chamber. If this pressure builds up sufficiently high, valve 49 is seated against the tension of spring 50 and the oil may escape into the end section 62 of the cylinder ahead of the moving piston. As the piston moves to the left, oil is forced out of the end 62 through the port 61 and passageway 60, against the surface of valve 63 and through the opening 69 of that valve into the valve chamber 67. Since the opening is small the pressure will overcome the tension of spring 64 and lift the valve 63 off of its seat permitting rapid escape of oil from the passageway 60 into the valve chamber 67 from which it escapes through the port 71 into the passageway 52 and back into the end 51 of the cylinder behind the retreating piston. Obviously this oil in the passageway 60 may also flow through the port 59 into the valve chamber 57 where it is obstructed by the valve 53 which is now closed.

The spring 57 is made considerably stronger than the spring 64 and consequently the valve 53 will be maintained upon its seat until a higher pressure is built up behind it than will the valve 63. The checking arrangement is therefore capable of producing a greater retarding effect when its shaft 27 is rotated in one direction than it is when it is rotated in the opposite direction. Preferably the device is mounted in such a manner that as viewed in Figure 4 the piston will move to the right when the carriage 7 is being brought to rest at the end of its travel from one of its extreme positions to the other, and the piston 38 will move to the left when the movement of carriage 7 is being started. By this arrangement a small opposition is afforded to the starting of the movement of carriage 7 and the carriage is therefore accelerated gradually, and a greater opposition is met when the carriage is being brought to rest and it is therefore decelerated quite rapidly. Since the pusher plate 41 is spring mounted with respect to the piston 38 the piston is gradually brought up to speed when the roller 29 engages the arm 28, and the application of the checking is therefore somewhat gradual and can be made without imparting a jar or shock to the door mechanism moved by the moving carriage.

Mounted upon the framework 3 of the door operator are limit switches 80 and 81 which are connected to the operating arms of the door checks 25 and 26 respectively. The details of these limit switches will be found in Figures 17

and 18. It will be seen that each switch comprises a base 82 preferably composed of an insulating material such as hard rubber or a phenol condensation product, upon which is mounted a pair 5 of brackets 83 in which is journaled a shaft 84 located at some distance above the upper surface of the base plate 82. The brackets 83 may be surrounded by insulating sleeves 83'.

Mounted upon this shaft 84 are cams 85 and 10 86, and a bell crank 87 the free end of which is connected to a tie rod 88 which in turn is connected to the operating lever 28 of the checking device. Thus it will be seen that a movement of the operating lever of the checking device will 15 rotate the shaft 84 and the cams 85 and 86 carried by it.

Mounted upon the base of the limit switch is a contact means 89 containing a movable contact 90 and a stationary contact 91 which are properly 20 maintained and operated by spring 97 which raises the camming lever 93 upon which the movable contact 90 is mounted. This camming lever engages the cam 86 carried by the shaft 84 and when the valley portion of that cam is engaging 25 the operating lever 93, the contacts 90 and 91 are opened. When the hill 86 of the cam engages the lever 93 that lever and the contact 90 carried by it are rotated about the pivot 94 to bring the contact 90 into engagement with the stationary 30 contact 91. The details of construction of this switching arrangement are more fully disclosed in my copending application Serial No. 607,688, filed April 27, 1932, to which application reference is here made for those details. The stationary 35 contact 91 is projected through the base 82 and provided with nuts 95 by means of which a suitable wire, not shown, may be connected to the contact. Other terminals 96 are provided, each consisting of a screw projected through the base 40 plate 82 and provided with nuts by which it is held in place on the base plate and by which wires are attached to it. The contacts 90 and 91 of the limit switches are connected in the electrical circuit to bring the motor 18 to rest when 45 the carriage 7 reaches its limit position and operates the checking device into the position shown in dotted lines in Figure 3. Obviously when the carriage is moved out of this position the shaft 84 will be rotated in an opposite direction and 50 contacts 90 and 91 will again be opened by the spring 97.

When the elevator is being moved up or down in its shaft the carriage 7 will be disposed at one end of its trackway 4, corresponding to the closed 55 position of the doors of the hatchway. The doors will be locked in position by a latching mechanism, such as is shown in Figures 7, 8, 9, and 10. This mechanism consists of a plate 100 mounted upon the door 101 in any preferred manner, such 60 as by bolts 102. The door in turn is mounted upon a stationary trackway 103 by suitable rollers, not shown.

The plate 100 contains an extension 104 upon which is mounted a mounting bracket 105 by 65 means of bolts 106 projecting through slots, not shown, in the extension 104 of the plate 100 to permit a limited lateral adjustment of the mounting bracket 105 in and out of the plane of the plate 100.

Carried upon this mounting bracket 105 is a 70 pivot shaft 107 upon which is pivoted a lever 108 which is held in place thereon by a nut 109 threaded onto the end of the pivot shaft 107. A spring 110 attached at one of its ends to the 75 lever 108 and at its other end to a portion of

the mounting bracket 105 is tensioned to rotate the lever 108 in a clockwise direction, Figure 8, about its pivotal axis 107 into the position in which it is shown in Figure 8.

The lever 108 contains a generally rectangular recess 111 bounded by projecting members 112 and 113. Preferably resilient inserts 114 and 115 are set in these projections and held in there in any convenient manner such as by rivets 116. These inserts may be of a phenol condensation 10 product, hard rubber, or fiber, as desired.

The lever 108 also contains a projecting lug 117 which engages a latch 118 that is pivoted at 119 to a portion of the mounting bracket 105. The free end of this latch contains a pawl 120 which 15 engages with stationary detent 121 mounted upon the carrier rail 103 in the elevator shaftway. With the pawl 120 of the latch lever 118 engaged with one of these detents 121, the door 101 is securely latched in its closed position. 20

The latch mechanism is shown in Figure 8 with the pawl 120 engaged with a detent 121 and with the door closed. The carriage 7 is shown in the position in which it is placed when the elevator is moving upwardly or downwardly in its shaft. 25 It will be noted that the shoe 8 lies adjacent to but does not engage the projection 113 of the lever 108. The elevator therefore is free to move upwardly and downwardly without obstruction from the latches on the doors in the hatchway. If 30 the carriage 7 becomes dislocated or one of the latches is out of place, and the shoe 8 engages with the projection 113 of that latch, or with some other projecting part of it, because of the tapered ends 12 of that shoe, it will be rotated in a clockwise direction, Figure 8, about its pivot 9 against the tension of spring 11 so that the shoe may pass the obstruction without breaking either itself or the latching lever 108.

When the carriage 7 is moved to the right to 40 unlatch and open the door, the shoe 8 engages the resilient block 115 located in the projection 113 and bears against that block to rotate the lever 108 in a counterclockwise direction about its pivot 107 against the tension of spring 124. This 45 brings the shoe into the recess 111 in the lever 108, that is between the resilient blocks 114 and 115. Since the shoe 8 engages the resilient block when it is brought into contact with the lever 108 the engagement is made without excessive noise, 50 which obviously is advantageous.

It will be noted that the projection 117 of the lever 108 normally rests in a recess 125 in the bottom of the latch 118, and obviously when the lever 108 is rotated in a counter clockwise direction and 55 the free end of the projection 107 is moved to the left, it will ride up over the boundary of this recess 125 and lift the latch into the position into which it is shown in the dotted line in Figure 9. This releases the pawl 121 and thereby unlatches 60 the door.

The mounting bracket 105 upon which the lever 108 is mounted contains a resilient insert 126 against which the end of the lever 108 comes to rest when it is rotated in a counter clockwise direction about its pivot. This block is resilient, the lever comes to rest without shock. Similarly, a resilient block 127 is provided on the opposite side of the mounting bracket 105 and the lever 108 comes to rest against this block when it is rotated 70 by the spring 110, as will presently appear.

As the movement of the carriage 7 continues the shoe 8 bears against the resilient lock 115 and moves the lever 108 in a translatory motion carrying with it the door 101 which is thus opened. 75

When the door is practically completely opened the carriage 7 engages the checking device 26, and its motion is therefore retarded down, and the motion of the door 101 is decreased gradually and 5 it is brought to rest without shock.

The shaft 107 upon which the lever 108 is mounted is provided with a depression or groove 128 into which the tip end of the plunger 129 fits when the lever 108 is rotated against the 10 silent block 126. A spring 130 fitted around the shaft 131 of the plunger and held under tension 15 by a plug 132 urges the plunger 129 into the groove 128 and thereby locks the lever 108 in its operated position in which it is shown in Figure 7, against the tension of spring 126. This insures that the lever will be maintained in its engaging position with respect to the shoe 8 during the normal operation of the device in moving the door 101.

20 When the motion of the carriage 7 is reversed the shoe 8 bears against the block 114 and moves the door 101 in the opposite direction towards its closed position. Should the door strike an obstacle which obstructs its path and prevents it 25 from closing, the tension placed upon the block 114 by the shoe 8 will overcome the forces locking the lever 108 in its operated position and that lever will swing into the position into which it is shown in Figure 8 to clear itself from the operating shoe 8. This clears the door from the operating mechanism, whose carriage 7 continues to move to its extreme position, and the door is then 30 manually closed after the obstruction has been removed.

35 Obviously the detachment of the lever 108 from the shoe 8 will occur when the door is completely closed and can be moved no further because of its stops and the apparatus will therefore be returned to normal position in which it is shown 40 in Figure 9. A movement of the lever 108 in a clockwise direction about its pivot 107 moves its projection 117 back into the recess 125 of the latch 118 and that latch is therefore permitted 45 to fall into engagement with the detent 121 to lock the door in its closed position.

It will be noted that when the lever 108 detaches from the shoe 8 to release the door from the operator because it has encountered an obstruction, the shoe and lever assume the position shown in Figure 8, except of course that the latch 118 is not engaged with the keeper 121 and the shoe 8 may be farther from the lever 108. When the door is closed and latched manually 50 the operator is capable of reoperating it without the performance of any resetting operations. The same is true if the door is not closed manually, but is left in an intermediate position, that is neither open nor closed. The resetting is 55 automatic in all instances and this arrangement is advantageous for many reasons. The automatic reset obviously reduces the time lost by a release of the door from the operator as above explained.

Frequently elevator cabs are provided with a 60 gate or door which must be closed before the car can be moved. If desired the carriage 7 may be provided with a projecting rod 140 which extends downwardly outside of the cab and engages with a plate 141 located on such inner door. 65 This plate preferably consists of a generally U-shaped bracket containing a socket 142 into which the lower end of the rod 140 is positioned. A spring pressed detent 143 registers with a 70 groove 144 in the end of the rod 140 and serves 75 to hold the rod in the pocket and consequently

in engagement with the gate or door of the elevator cab. The plate 141 is so located upon the cab door that the rod 140 is moving to the left, Figure 17, when the door of the cab is being closed. Obviously if the door or gate of the cab 5 comes into contact with a passenger or with anything that tends to obstruct its free movement, the rod 140 will be pulled out of the socket 142 and the gate will therefore be stopped. The carriage 7 will of course continue to its normal 10 position as if nothing had happened. By this arrangement, the gate as well as the hatchway door may be closed by door operator with the full assurance that passenger in the elevator will not be injured by accidentally coming into contact with the moving gate. The engagement of the rod 140 with the cab gate is reestablished by a movement of the rod to the right, Figure 16, or of the gate and plate 141 to the left, this resetting 15 obviously being automatic as the gate is closed. 20

It is generally most desirable in a device of this kind to provide an arrangement for preventing the door operator from functioning if the elevator is not properly aligned with the floor level. Usually the elevator must be within two or three 25 inches of the floor in order for the operator to function. To this end I have provided an improved range relay shown in Figures 11, 12, 13 and 14 which is connected into the control circuit of the door operator in such a manner as to 30 prevent its functioning until the elevator is brought within the prescribed distance of the floor level.

This range relay comprises a base 150 preferably made of an insulating material such as a 35 phenol condensation product or hard rubber, and upon which are mounted journal posts 151 and 152. Two substantially parallel shafts 153 and 154 are journaled in these posts 151 and 152. Mounted on the shaft 154 is an armature 155 40 composed of magnetic material and registering with the coil 156 of an electromagnet 157 which is mounted upon the base 150. A suitable back stop 158 is mounted upon this electromagnet and serves as a support for the armature 155 when 45 it is in its normal position, in which it is shown in Figure 11.

The shaft 154 also carries a block-like member 159 upon which is mounted a lever 160 projecting upward alongside the armature 155. A contact 50 bracket 161 is also mounted upon this block 159 alongside the member 160.

The shaft 153 carries a lever 162 upon which is mounted a pin 163 around which is a coil spring 164. This pin projects through a perforation in the lever 160 and is locked therein in any preferred manner, such as, for example, by means of a cotter pin 165. The head of the pin 163 bears against the opposite face of the lever 162. Attached to this lever 162 is an insulating member 60 166 which carries a contact 167 which is thereby held in substantial alignment with a contact 168 carried by the contact arm 161 of the shaft 154.

The shaft 153 projects beyond the journal posts 151 and 152 and a camming lever 169 is mounted 65 upon the projecting end of this shaft in any preferred manner such as by the set screw 170. The free end of this camming lever 169 carries a roller 171 which is adapted to engage with stationary cams such as 172 located in the elevator 70 shaft, as will presently appear.

Normally the range relay mechanism assumes the position in which it is shown in Figure 11, and the camming lever 169 is positioned with respect to the base 150 in such a manner that 75

it does not engage with the cams 172 as the elevator is moving in the shaft. When it is desired to stop at a particular floor, a control lever in the cab is operated and the electromagnet 157 is energized. This magnet attracts the armature causing the shaft 154 to rotate in a counter-clockwise direction into the position in which it is shown in Figure 12. The lever 160 pushes against the spring 164 and the shaft 153 is rotated thereby to move the free end of the camming lever 169 outwardly from the base 150 into such position that it will strike against the cam 172 when the elevator reaches the proper position in the shaft.

As soon as the roller 171 engages the cam 172 shaft 153 is rotated in a clockwise direction and the contact 167 carried thereby is brought into engagement with the contact 168 carried by the shaft 154. The electrical circuit of the elevator operator is extended through these contacts and rendered operative when these contacts 167 and 168 are closed, so that the door operator may function to open the door in the hereinbefore explained manner. As shown, contacts 167 and 168 are spring mounted upon their respective levers so that they are capable of considerable movement toward each other and when engaged are put under considerable tension by their springs so that a good electrical contact is assured. The contacts slide with respect to each other upon being engaged and are therefore self cleaning. When the magnet 157 is deenergized the armature falls back into the position in which it is shown in Figure 11 and contacts 167 and 168 are separated by the tension in springs 164.

After an elevator stops at a particular floor and the doors have been opened, it is important that the elevator is not started until those doors are again completely closed and latched. This may be accomplished by placing a switch 180 upon the guide rail 103 of the door and mounting a camming block 181 upon the door itself. Obviously, as the camming block is moved into engagement with the spring 182 of the switch 180 it will operate that switch and close an electrical circuit through it which circuit can be utilized to control the starting of the elevator. Switch 180 may conveniently be a switch of the type more fully disclosed in my copending application, hereinbefore referred to.

Furthermore it is important that the elevator be held at the floor level until the door operating mechanism returns to its normal position, to guard against the possibility of the operating shoe 8 striking an obstacle as the car is moved. To this end, a switch 183 operated by the cam 85 of the limit switch assembly hereinbefore referred to can be and preferably is included in the control circuit of the elevator motor, so that motor cannot be started until the door operating mechanism is in its normal position.

In Figure 20 I have shown a representative circuit diagram illustrating by the usual circuit symbols one manner in which the devices of my invention may be connected together electrically in conjunction with the control apparatus of the elevator. This circuit diagram is shown by way of example only as there are many other circuit arrangements which may equally well be used to connect the devices of my invention into an operative system.

Referring now to Figure 20 in more detail, the elevator hoisting equipment comprises the elevator hoisting motor 320, the elevator direction switches 321 and 322, switch 321 containing contacts 323 and 324 for governing the upward movement of the elevator, and switch 322 containing contacts 325 and 326 for governing the downward movement of the elevator, the relays 327 and 328 for operating the switches 321 and 322, respectively, the door interlock contacts 329, of which there is one disposed on each hatchway door on each floor, the hoisting motor brake 330, which is shown, for example, as of the common spring applied electromagnetically released type, and the car switch 331, which is mounted in the elevator and is adapted to operate the "up" and "down" contacts or switches 332 and 333, respectively. When the elevator operator desires to move the elevator in an upward direction, he rotates car switch 331, thereby closing contact 332. A circuit may now be traced from line conductor 217, through the interlock contacts 329, through the motor brake 330, through contact 332 of car switch 331, through relay 327 and thence to line conductor 216. The motor brake 330 is energized and thereby released from its applied position over this circuit, and the relay 327 is energized over this circuit to close switch 321 against contacts 323 and 324. A circuit may now be traced from line conductor 217, through contact 324 to the hoisting motor 320, and from hoisting motor 320 to contact 323 and thence to line conductor 216. The hoisting motor will be operative over this circuit to raise the elevator. Likewise, when it is desired to move the elevator downwardly, the car switch 331 is rotated to close contact 333. A circuit may now be traced from line conductor 217, through the interlock contacts 329, through the motor brake 330, through contact 333 of car switch 331, through relay 328, and thence to line conductor 216. The motor brake 330 is energized and thereby released from its applied position over this circuit, and the relay 328 is energized to close switch 322 against contacts 325 and 326. A circuit may now be traced from line conductor 217, through contact 326, to the hoisting motor 320, and from the hoisting motor 320 to contact 325, and thence to line conductor 216. It will be observed that the application of voltage across line conductors 216-217 is in the opposite direction to what it was when the elevator was being raised, and the motor will therefore operate in the opposite direction over this circuit to lower the elevator.

It will be noted that as the interlock contacts 329 are included in the circuits of the relays 327 and 328, that these contacts must be closed in order that the relays may be energized to close the direction switches 321 and 322. The opening and closing of contacts 329 are controlled by the hatch-way doors, and these doors must all be closed in order that the relay circuits may be energized. If one of the doors is open, the relay circuits will likewise be open and consequently the brake motor cannot be energized to release the brake from its applied position, nor can the direction switches 321 and 322 be closed. The elevator, therefore, cannot be started until the door is completely closed and latched.

Referring now in more detail to the door controlling equipment shown in Figure 20, the apparatus to the left of the dotted line may conveniently be located on the elevator control panel, which frequently is located in the pent house at the top of the elevator shaft. This equipment consists of a terminal block 200 containing a plurality of individual terminal members of any preferred design to which the connecting wires may conveniently be attached. The control ap-

paratus also comprises a shut relay 201 containing contacts 202 and 203 and a second pair of contacts 204 and 205 which are operated to their respective closed positions when the magnet of the shut relay 201 is energized.

The control equipment also comprises an open relay 206 which contains two pairs of contacts 207 and 208 and 209 and 210, which contacts are closed when the winding of the relay 206 is energized. The control equipment also comprises an interlocking relay 211 which controls a single pole, double throw switch comprising contact 212 which engages with contact 213 when it is in its normal position with the winding of relay 211 de-energized, and a contact 214 which is engaged by the contact 212 when the winding of relay 211 is energized.

Relays 201, 206 and 211 may be varied in mechanical design within the teachings of my invention and the mechanical details of them have therefore been omitted. There are a number of relays commercially available which may be used in the circuit shown.

The common control equipment also consists of a pair of contacts 215 which are closed when the main brake 330 of the elevator motor 320 is applied.

Line terminals 216, 217 and 218 are connected to individual terminal lugs on the terminal block 200. A cable, indicated generally at 219, connects the terminal block 200 to a second terminal block 220 carried by the elevator. This cable may be of any preferred design and construction within the teachings of my invention.

The terminal block 200 contains a plurality of individual contacts to which the conductors of the cable 219 are connected and also to which the wires leading to the various instrumentalities carried by the elevator are likewise connected.

The motor 18, by which the door operator mechanism is actuated, contains three terminals 221, 222 and 223 through which the motor is actuated to operate in either one of two directions. The range relay, illustrated in Figures 11 to 14, inclusive, has its magnet 157 connected to terminals from the terminal block 220 and the contacts 168 and 167 controlled by this range relay are similarly connected. The open limit switch contacts 90 and 91 and the shut limit switch contacts 90' and 91' are likewise connected to the terminal block 220. A pair of auxiliary contacts 224 and 225 are included in the control mechanism of the elevator to be closed by the car switch 331 when that switch is moved to start the car either in an upward or a downward direction. When the control mechanism of the elevator is in its normal position, that is with the main motor of the elevator idle, these contacts 224 and 225 are opened.

Assuming now that the elevator is standing at a floor level and that the hatchway door is open. The open limit switch comprising contacts 90 and 91 will be positioned so that these contacts are opened. When the elevator operator desires to close the hatchway doors and start the car, he operates the elevator car switch 331 to close contacts 224 and 225.

A circuit may now be traced from line conductor 216 to contacts L-3 and M-3 in the terminal strip 200, through the cable 219 to terminal CS-2 in the terminal block 200, thence through the contacts 224 and 225 to the terminal CS-1, through the cable 219, through the terminal CS, through the winding of interlock relay 211, and thence back through the L-1 contact

of the terminal block 200 to the line conductor 216. This energizes the interlocking relay 211, which closes contact 212 against contact 214 and opens it away from contact 213. A circuit may now be traced from the line conductor 216 to the L-1 terminal block and contacts 212 and 214, through the winding of relay 201, through the SL contacts of terminal blocks 200 and 220, through the shut limit contact 90' and 91', and thence through the line conductor 218 through the terminal LC in the block 220 and terminals M-3 and L-3 in the block 200. The shut relay 201 energizes over this circuit and closes contact 204 against contact 205 and contact 202 against contact 203. A circuit to the motor 18 may now be traced from line conductor 216 through contacts 204 and 205, through M-2 contact of terminal block 200, through the cable 219 to the M-2 terminal block 220, thence through the terminal 221 of the motor, through that motor and the terminal 222, through the neutral line conductor 218 over the previously traced circuit. A second circuit to the motor may also be traced from the line conductor 217 through closed contacts 202 and 203, through the M-1 terminals in blocks 200 and 220, to the terminal 223 of the motor. Motor 18 is energized over this circuit and revolves in such a direction as to move the carriage 7 to close the doors of the hatchway. When the door reaches its limit position the shut limit contacts 90' and 91', are opened whereupon the circuit of relay 201 is opened and that relay falls back to open contacts 204 and 205 and 202 and 203 and thereby bring the motor 18 to rest. The operator then actuates the car switch 331 in the elevator to open contacts 224 and 225 and to close the contacts 332 or 333 through which the movement of the elevator is controlled, and the elevator moves away from the floor at which it was stopped.

When the elevator is moving toward the floor at which it is to stop and at which the hatchway doors are to be opened, contacts 224 and 225 are open. The motive power of the elevator is turned off, by rotating the car switch 331 to the position shown in Figure 20, thereby opening the contact 332 or 333, whichever one may have been closed, and deenergizing its associated relay circuit and opening the car direction switch. Deenergization of this relay circuit will cause the motor brake 330 to be applied and contacts 215 controlled, thereby will be closed. Upon the closing of these contacts, a circuit may be traced from line conductor 216 through contacts 212 and 213 which are now closed, through the brake contacts 218, through the terminals R of the terminal blocks 200 and 220, through the winding 157 of the range relay, through the open limit contacts 90 and 91, which will be closed because the carriage 7 of the operator is in the position corresponding to the closed positions of the doors, and thence back to the line conductor 218 through the contact LC of the terminal block 220 and the contacts L-3 and M-3 of the terminal block 200. Range relay is energized over this circuit and its camming lever 169 projected outward into position to engage the cam 172 located adjacent to the floor at which the doors are to be opened. When the cam 172 is engaged contacts 167 and 168 are closed and the open relay 206 is energized over a circuit traceable from a junction of the previously traced circuit from line conductor 216 through the brake contact 215, through the winding of relay 206, through the contacts RC in the ter-

5 minal blocks 200 and 220, through contacts 167 and 168, through terminal BL in terminal block 220 to the cut-out switch, from the cut-out switch through open limit contacts 90 and 91, 5 to the line conductor 218 over the previously traced circuit. It may here be stated that the cut-out switch is normally closed, but if it is desired to prevent operation of the automatic door operator, the switch is opened. Relay 206 10 energizes over this last mentioned circuit and closes the contact 209 against the contact 210 and the contact 207 against the contact 208 thereby completing a circuit to the motor 18 which is traceable from the line conductor 216 15 through contacts 209 and 210 and thence through the terminal blocks and cable to terminal 223 of the motor. A second circuit to the motor is closed from line conductor 217 through contacts 207 and 208 and then through 20 the terminal 221 through the terminal blocks 200 and 220 and the cable 219. The circuit from the line conductor 218 to the terminal 222 remains closed, as before. It will be observed that the application of voltage across the line 25 conductors 216—17— and 18 is in the opposite direction to what it was before, and the motor will therefore operate in the opposite direction and move the carriage 7 in such direction as to engage the latching mechanism of the door and 30 to open that door. When the door reaches its open position, open limit contacts 90 and 91 are opened, the relay 206 falls back, and the circuit to the motor 18 is broken and that motor comes to rest. 35 Thus it will be seen that the foregoing circuit connections may be used to connect the instrumentalities of my invention into a single complete system for automatically opening and closing the doors of an elevator or similar structure 40 responsive to the actuation of a single control lever located within easy reach of the elevator operator. The foregoing circuit is but one of the many which may be used for this purpose, and I do not wish to be limited to the precise 45 circuit details which are shown by way of example.

The devices hereinbefore described may be advantageously modified to meet particular conditions within the teachings of my invention. In 50 Figures 21, 22 and 23 I have shown a modified form of operator unit which in certain instances can be used advantageously over the unit shown in Figure 1. It will be seen that the modified form of operator comprises a suitable framework 55 3' which is similar to the previously described framework and carries the rail 4' upon which the operator carriage is mounted. The carriage 7' carries the operator bar 8' which is mounted in a slightly different manner so that it is normally retracted into closer relation with the carriage 7'. This arrangement permits the operator to be used in hatchways where the clearance between the car and the hatchway wall may be too small to permit satisfactory operation of 60 the device shown in Figure 1, since the operator arm 8' is retracted into the operator mechanism when the elevator is in motion and less clearance space between the car and the elevator hatchway is required. 65

65 The carriage 7' is operated by chain 18' which is threaded over sprocket wheels 14' and 15', as before. Sprocket wheel 15' is driven from a gear driven by a motor 18' through the speed reducing mechanism 16'. This mechanism is connected to the shaft upon which the sprocket

75 wheel 15' is mounted by a suitable chain 230 threaded over a sprocket wheel carried by the speed reducing mechanism shaft 231 and also threaded over a sprocket wheel 232 carried on the shaft upon which sprocket 15' is mounted.

The operator shown in Figures 21 to 23 inclusive, further differs from the previously explained unit in that the motor, speed reducing mechanism, and carriage operating mechanism are all carried as a unit upon the frame work 3'. To this end a platform like frame 233 is supported upon the main frame work 3' by suitable brackets 234 and serves as a mounting base for receiving the motor and speed reducing mechanism. The unit thus formed can be installed upon the elevator with a minimum of labor. The arrangement is further advantageous in that the operating mechanism of the operator may be covered by a suitable cover 235 detachably mounted upon suitable posts 236 carried by the mounting base of the unit. Such a cover will obviously protect the working parts from dust and dirt.

In Figures 21 to 23, inclusive, I have shown checking devices 25' and 26' which are of a slightly different type than the devices 25 and 26 hereinbefore explained. These devices 25' and 26' are single acting checks which serve to bring the operator mechanism to rest, as will herein-after appear. The checking devices 25' and 26' may also be used in the mechanism shown in Figure 1 should it be desirable to do so. These checking devices are operated by arms 28', as before, and limit switches 80' and 81' are connected to these arms. It will be noted that these limit switches are mounted close together and near the center of the mechanism, in which position they may be conveniently covered by a separate cover should it be desirable to do so.

In Figures 23, 26 and 27, I have shown a modified form of latch and keeper, and have also shown the details of the mounting of the operator bar 8' on the carriage. It will be seen that the operator bar 8' is a vertically disposed member having beveled ends, as before, and is carried upon two horizontally disposed arms 240 and 241 which are pivoted to the carriage 7' by suitable pivots 242. A projection 243 of the arm 240 extends beyond the vertical bar 8' and is pivotally connected to a spring pressed rod 244, which rod is in turn pivoted to the carriage 7' at 245. The tension of the spring 246 urges the arms 240 and 241 in a clockwise direction about their pivots 242 to extend the operating bar 8' out into the space between the elevator and the hatchway walls. The free end of the arm 241 is beveled at 247 and is adapted to engage a roller 248 when the operator approaches the position which it occupies when the doors of the hatchway are closed in readiness for moving the elevator away from the floor. Roller 248 may conveniently be a ball bearing which is mounted upon the framework 3 of the operator in any convenient manner.

By this arrangement when the operator carriage is moved into its normal position, in which it is shown in Figure 26, the beveled portion 247 of the arm 241 rides over the bearing 248 and rotates the operating arm in a counterclockwise direction about its pivotal axis 242 against the tension of spring 246. This retracts the operator bar 8' from the latch mechanism of the elevator 7 door and into a position immediately adjacent to the carriage 7 in which position it can move up and down in the elevator shaft without striking any obstruction. Arm 240 carries an adjusting screw 249 adapted to bear against the block 7

250 carried by the carriage 7 to thereby limit the movement of the operator bar outwardly from the carriage.

In Figures 24, 25, 26 and 27 I have shown a modified form of latch and keeper mechanism for the hatchway door, which mechanism can be used advantageously either with the form of operator shown in Figure 1 or with the modified form shown in Figures 21 to 23, inclusive. The modified form of latch shown in these latter figures occupies less space in the hatchway than the latch mechanism shown in Figures 7 to 9, inclusive, and is therefore advantageous for use in installations where the clearance space between the hatchway walls and the elevator is rather small. As will be seen in Figures 24 and 25 the latch mechanism comprises a mounting plate 100' adapted to be attached to the hatchway door. Usually this bracket will be mounted upon the roller bracket 252 by which the door is mounted upon the rail 253 along which it slides to open. The mounting bracket 100' is generally L-shaped as before.

Adjustably mounted upon the flat upper portion 254 of the bracket 100' is a stationary keeper plate 255. A movable latch 256 is mounted upon this plate by pivotal means 257 and urged to rotate in a counterclockwise direction, Figure 26, by a spring 258. A pin 259 carried by the latch 256 strikes against an edge 260 of the stationary plate 255 to limit the rotation of the latch 256 under the action of spring 258.

Stationary plate 255 and latch plate 256 together form a generally rectangular socket 261 into which the operator bar 8' is moved, as shown in Figure 27.

The keeper plate 262 is carried by the brackets upon which the rod 253 is supported and contains projecting ears 263 with which the tongue portion 264 of the latch lever 256 are registered to lock the doors in their closed position.

In the operation of the device, when the carriage 7 is moved to the left, Figures 26 and 27, under the action of motor 18', the tapered portion 247 of the operator bar rolls off of the bearing 248 to permit the spring 246 to rotate the arm in a clockwise direction to thereby bring the operator bar 8' into registration with the socket 261 in the latch mechanism. This arm 8' strikes against the edge of the plate 256 and rotates that plate in a clockwise direction about its pivot against the tension of spring 258. This rotation withdraws the latch tongue 264 from the ear 263 of the keeper plate to unlatch the doors and permit them to be moved upon their rail 253. The continued operation of the carriage 7' serves to move the doors from their closed to open position.

It will be noted that the line of thrust from the carriage 7' to the latch mechanism is not straight. In the event that the door strikes an obstruction, when moving to closed position, which is to the right as viewed in Figure 27, and the tension placed upon this line of thrust is therefore excessive, such tension will have a component tending to rotate the operator arm 240 about its pivot 242 against the compression of spring 246. The latch mechanism 256 will also be rotated about its pivot 257, by reason of the tension imposed upon the arm 240 and the arm 240 will rotate free from the latch mechanism and thereby release the operator from the door. The carriage 7' will then continue on to its extreme position and the door is then manually closed after the obstruction has been removed. A subsequent movement of the carriage in either

direction will cause the bar 8' to ride over the beveled surfaces of the latch mechanism into engagement with the socket 261 to permit moving the door after the obstruction has been cleared.

The latch 256 is provided with an arm 265 which is adapted to be engaged by a rod 266 journaled to the door as at 267. Suitable manual means are adapted to move the rod to cause it to unlatch the doors, should manual operation of the same be desirable. This manual means may be of any desired construction. For example, it may comprise a bell crank lever 320 pivotally mounted at 321 upon the elevator door. One arm 323 of this lever has the rod 266 pivotally secured thereto at 324 and the other arm 325 of the lever has one end of a push rod 326 pivotally secured thereto at 327. The other end of push rod 326 is pivotally secured at 328 to an operating handle 329, which handle is pivotally secured at 330 to a plate 331, suitably secured to the elevator door. Moving the handle 329 to the left, as shown in Figure 26, will force the push rod 326 upwardly, thereby revolving the bell crank lever about its pivot 321 and forcing the rod 266 to the right, as viewed in Figure 26. As the rod 266 engages the arm 265 of the latch mechanism 256, such movement of the rod 266 to the right will revolve the latch about its pivot 257 and thereby unlatch the door.

The latch and keeper mechanism shown in Figures 24 to 27, inclusive, includes also a set of interlocking contacts through which the operation of the driving motor of the elevator is controlled to prevent the elevator from being moved until all of the hatchway doors are closed and locked. This interlocking device comprises a pair of stationary contacts 270 and 271 carried upon a suitable insulator plate 272 within a housing 273 which is mounted upon the bracket which holds the keeper plate of the latch. Circuit connections 274 are extended through a suitable conduit 275 to these contacts.

A bracket member 276 is attached to the latch 256 and upstands therefrom in juxtaposition to the contacts 270 and 271. An insulator 277 is mounted upon the bracket 276. A square post 278 is attached to this insulator and projects therefrom toward the contacts 270 and 271. A short circuiting bar 279 is slidably mounted upon the post 278 and is spring-pressed away from the insulator 278 by the coil spring 280. When the latch lever 256 is in its closed position, that is with the doors locked shut, short circuiting bar 279 engages the contacts 270 and 271 to electrically connect the same together, thereby completing the series interlocking circuit through these contacts. When the latch 256 is rotated to unlock the doors the bar 279 is moved away from these contacts to thereby break the interlocking circuit and prevent further movement of the elevator.

In Figures 30 and 31 I have shown a modified form of elevator shaft gate operator comprising a bar 140' carried by the carriage 7' and carrying a latch 281 which is notched to engage a pin 141' carried by the gate. The latch 281 is pivoted to the bar 140' at 282 and urged downwardly upon the pin 141' by a spring 283. An adjusting screw 284 carried by the latch 281 bears against the bar 140' to limit the movement of the latch. By this arrangement the gate of the elevator cab is opened and closed simultaneously with an opening and closing of the hatchway doors by the operator mechanism. In the event that the gate strikes against an obstruction latch 281 is ro-

tated in a counterclockwise direction about its pivot 282 against the tension of spring 283 to release the pin 141 therefrom to permit the gate to come to rest independently of the operator. 5 By this arrangement the danger of injury to a passenger in the car by reason of coming into contact with the mechanically operated gate is eliminated.

The modified door check shown at 25' and 26' 10 in Figures 21 to 23, inclusive, is shown in detail in Figures 28, 29 and 30. This check comprises a suitable casing 290 through which the shaft 27' is projected. This shaft carries the operating lever 28' by which the check is connected with 15 the moving carriage of the operator to retard the movement of that carriage. Within the casing 290 the shaft 27' carries a bell crank 291 keyed thereto by suitable means such as a set screw 292. Within the casing is a cylinder 293 in which a 20 piston 294 is fitted. This piston contains an ear 295 which projects from the closed end 297 of the piston, which ear is connected to the bell crank 291 by a pair of links 296 disposed upon opposite sides of the ear 295 and crank 291 and suitably 25 pivoted thereto.

The piston contains a disk-like wall 297 which contains a centrally located port 298 closed by a plate or valve 299 that is pressed thereagainst by a spring 300. The ear 295 contains a centrally located boss 301 which in turn carries a post 302 upon which the gate or valve 299 is slidably mounted and around which the spring 300 is disposed.

Projecting from the piston head thus formed 35 is a piston skirt or hollow cylinder in the walls of which are located a plurality of large ports indicated at 303. Leading out of the cylinder 293 is a port 304 normally closed by a valve 305 spring-pressed against its seat by a suitable coil 40 spring 306. The valve stem 307 and coil spring are held in place in the casing 290 by a suitable bushing 308 threaded therein. The tension of the spring 306 is adjusted by moving this bushing 308 inwardly or outwardly of the casing with a wrench 45 engaging the squared head 309 of the same. A suitable cap 310 and lock nut 311 are threaded upon the bushing 308 to maintain the adjustment intact once it has been set. The chamber within the casing 290 is completely filled with oil, 50 or an equivalent fluid.

In the operation of the check, with the parts thereof in the position in which they are shown in Figure 28, the operator is in its normal position ready to resist movement of the carriage into 55 its limit position. The normal position of the check is determined by the adjusting screw 320 which engages the operating arm 28' to position it. The roller 28' carried by the carriage engages the operating arm of the check and rotates the 60 shaft 27' in a counterclockwise direction to move the piston 294 to the right, Figure 28, against the pressure of the oil confined in the cylinder 293. It will be noted that this pressure aids the pressure of spring 300 in maintaining the valve 299 closed so that no oil can leak therethrough. At 65 the beginning of the movement of the shaft 27', ports 303 in the piston skirt register with a V-shaped slot 312 in the cylinder wall, to permit the escape of oil from the cylinder. The initial 70 movement of the piston is therefore relatively unresisted and as the piston moves to the right, the slot 312 is gradually closed to seal the cylinder and build up oil pressure therein. As the piston continues to move to the right the pressure in 75 the cylinder 293 is increased until it is sufficient

to unseat the valve 305 and permit gradual escape of the oil from the cylinder into the chamber 313 in which the bell crank is located. At the time that the valve 305 is unseated, the piston will have been moved to the right sufficiently to position the skirt 294 across the port 304. With the piston in this position the right hand one of the ports 303, Figure 28, is registered with the port 304. Oil can flow through the ports 303 and 304 into the hollow space 314 within the valve 305. 10 Ports 315 lead radially outwardly from the valve and communicate with an annular groove 316 which extends around the valve. When the valve is raised, this groove 316 is registered with the valve seat to permit the escape of the oil. The 15 passageway through which the oil is permitted to escape is not large and the movement of the piston is retarded by the pressure in the cylinder 293. By this arrangement the check opposes the movement of the carriage by an amount which 20 gradually increases to thereby decrease the speed of the carriage and thereby gradually bring it to rest without shock.

When the carriage of the operator is moved in the opposite direction the shaft 27' is rotated in a 25 clockwise direction and bell crank 291 thereby operated to move the piston to the left into the position in which it is shown in Figure 28. This movement immediately decreases the pressure in the cylinder and causes valve 305 to be reseated 30 and thereby close off port 304. Pressure is now built up upon the front side of the piston head 297 against the valve 299, this pressure soon overcoming the pressure of the spring 300 to unseat the valve and permit flow of oil through the port 35 293. Since this port is large oil rapidly flows into the cylinder and the resistance to movement of the shaft 27' is small. The checking device therefore is effective to introduce a large resistance to movement of its shaft in one direction 40 and a very small resistance to movement of its shaft in the opposite direction. By this arrangement the carriage of the operator can be rapidly brought to rest without shock and at the same time the carriage can be started in a reverse direction from rest without encountering an appreciable resistance from the checking mechanism. With the checking device of the type shown in Figure 28 the usual electromagnetic devices by which motor circuits are controlled to 50 bring the motor gradually up to speed may conveniently be used in connection with motor 18 if desired, such devices being well known and commercially available, have been omitted from the drawings as unnecessary.

What is claimed is:

1. A door operator mechanism for opening and closing the hatchway doors of an elevator comprising, a carriage mounted on the elevator, means on the elevator for moving said carriage, 60 a latch on each door in the hatchway, a keeper plate mounted in the hatchway and engaged by said latch to lock the door closed, an operator bar carried by said carriage including a lever pivoted thereon intermediate its ends, means associated with the opposite ends of said lever and operated by a movement of said carriage for moving said bar outwardly from the carriage into engagement with the latch of one of said doors to operate the same first to unlock and then to open said door, means associated with said lever for disengaging the same from said latch when the movement of the door is obstructed, and a pair of interlocking circuit contacts opened by the movement of said latch in 75

- unlocking the door to prevent movement of the elevator until the door is again locked closed.
2. An elevator door opening device comprising a stationary rail, a carriage slidably mounted on said rail, means for moving said carriage from one end of the rail to the other, and hydraulic means including a rotatable arm directly engageable by said carriage for resisting the movement of said carriage adjacent to ends of said rail.
- 10 3. An elevator door opening device comprising a stationary rail, a carriage slidably mounted on said rail, means for moving said carriage from one end of the rail to the other, and hydraulic means including a rotatable arm disposed in the path of movement of said carriage and engageable thereby for offering a large resistance to movement of the carriage toward the ends of the rail and a lesser resistance to movement of the carriage away from the ends of the rail.
- 20 4. An elevator door opening device comprising a stationary rail, a carriage slidably mounted on said rail, means for moving said carriage from one end of the rail to the other, hydraulic means including a rotatable arm directly engaged by the carriage when it is in the region of the end of the rail for resisting its movement, and valve means in said hydraulic means for governing the amount of said resistance.
- 5 30 5. An elevator door opening device comprising a stationary rail, a carriage slidably mounted on said rail, means for moving said carriage from one end of the rail to the other, hydraulic means including an arm disposed in the path of movement of said carriage and engageable thereby for resisting the movement of said carriage adjacent the ends of the rail, and contact means controlled by said hydraulic means for stopping the carriage at predetermined points on said rail.
- 40 6. An elevator door opening device comprising a stationary rail, a carriage slidably mounted on said rail, a pair of wheels mounted adjacent said rail, a motor, gears connecting the motor to one of said wheels, contact means for controlling said motor to stop said carriage, cams for operating said contact means, and levers engaged by said carriage for operating said cams to control said contacts.
- 50 7. In combination with an elevator adapted to move up and down in a shaft, and a plurality of hatchway doors of a latch member carried by each door, a latching lug mounted adjacent the door and engaged by the latch, a carriage carried by the elevator, a shoe pivoted to said carriage, a lever separate from said latch and pivoted to the door and including means engaging with said latch, means for moving said carriage to bring said shoe into engagement with said lever first to rotate it about its pivot to move said latch away from said lug and then to move it and its pivot to open said door.
- 60 8. In combination with an elevator adapted to move up and down in a shaft, and a plurality of hatchway doors of a latch member carried by each door, a latching lug mounted adjacent the door and engaged by the latch, a carriage carried by the elevator, a shoe pivoted to said carriage, a lever separate from said latch and pivoted to the door for swinging movement about an axis disposed at right angles to the pivotal axis of said latch and including means engaged with said latch, means for moving said carriage to bring said shoe into engagement with said lever first to rotate it about its pivot to move said latch away from said lug and then to move it and its pivot to open said door, and means for preventing an op-
- eration of said moving means until said elevator reaches a predetermined position with respect to said hatchway doors.
9. In combination with an elevator adapted to move up and down in a shaft, and a plurality of hatchway doors of a latch member carried by each door, a latching lug mounted adjacent the door and engaged by the latch, a carriage carried by the elevator, a shoe pivoted to said carriage, a lever pivoted to the door for swinging movement about an axis disposed at right angles to the pivotal axis of said latch and engaged with said latch, means for moving said carriage to bring said shoe into engagement with said lever first to rotate it about its pivot to move said latch away from said lug and then to move it and its pivot to open said door, said means including a chain attached to the carriage and engaged with a motor driven sprocket wheel.
- 10 20 10. In a latching device for elevator hatchway doors, a plate attached to the door, a bracket mounted on the plate, a lever pivoted to said bracket for movement about an axis parallel to the plane of the plate, said lever having a pair of bosses spaced apart and projecting from one of its sides, resilient inserts projecting from the working faces of said bosses, a resilient stop on said bracket, a spring attached to said lever and tensioned to rotate it about its pivot against said stop, and a second resilient stop on said bracket against which said lever is moved by a moving member engaging said bosses, and a latch means operated by movements of said lever.
- 25 30 11. A latch for elevator hatchway doors comprising a plate attached to the door, a bracket attached to said plate, a lever pivoted to said bracket, a latch pivoted to said bracket, said lever having a projection engaging said latch, and a spring attached to said lever and tensioned to rotate said lever about its pivot toward said latch.
- 35 40 12. A latch for elevator hatchway doors comprising a plate attached to the door, a bracket attached to said plate, a lever pivoted to said bracket, to swing in a plane substantially normal to the plane of said plate, a latch pivoted to said bracket, for movement in the plane of said plate, said lever having a projection engaging said latch, and a spring attached to said lever and tensioned to rotate said lever about its pivot toward said latch.
- 45 50 13. A latch for elevator hatchway doors comprising a plate attached to the door, a bracket attached to said plate, a lever pivoted to said bracket, a latch pivoted to said bracket, said lever having a projection engaging said latch, a spring attached to said lever and tensioned to rotate said lever about its pivot toward said latch, and a spring pressed plunger for holding said lever in the position to which said first named spring moves it.
- 55 60 14. A latch for elevator hatchway doors comprising a plate attached to the door, a bracket attached to said plate, a lever pivoted to said bracket, a latch pivoted to said bracket, said lever having a projection engaging said latch, a spring attached to said lever and tensioned to rotate said lever about its pivot toward said latch, and a spring pressed plunger carried by said lever and engaging the pivot thereof for holding said lever in the position to which it is moved by said first named spring.
- 65 70 15. In a door operating mechanism a latch means on the door, a lever included in said means, a movable shoe, means for moving said
- 75

shoe into engagement with said lever to cause the same to operate said latch means and then open said door, means associated with said lever for disengaging the same from said shoe when the movement of said door is obstructed, said means automatically resetting the lever in position for reengagement with said shoe.

16. In a latch operating device, a lever pivoted to a sliding door, a spring attached to the lever and tensioned to rotate its free end against said door, spaced bosses projecting from the side of said lever away from said door, a carriage mounted for translatory movement in the same direction as said door, a shoe pivoted to said carriage, a spring engaging said shoe and tensioned to move its free end away from said carriage, means for moving said carriage, said shoe being thereby moved into engagement with said projections to first rotate the lever about its pivot and then to move the lever and door, said shoe pivot and spring constituting means for permitting said shoe to disengage itself from said lever if said moving door strikes an obstruction.

17. In combination with an elevator car adapted to move up and down in a shaft, and a plurality of doors in said shaft through which access to said elevator car is gained, of means carried by said car and adapted for movement with respect thereto, means including a lever pivoted on said doors for swinging movement in a plane at right angles to the plane of said doors and engaged by said first means as it is moved to open and close the doors, means included by said last named means for permitting the first named means to disengage itself from the lever should the door strike an obstruction, a motor for moving said first means, and means carried by the car for preventing an operation of said motor

until the elevator is in a predetermined position with respect to said doors.

18. An elevator door operating device comprising a stationary rail, a carriage slidably mounted on said rail, means for moving said carriage from one end of the rail to the other, a door engaging lever pivotally mounted on said carriage for swinging movement in a horizontally disposed plane, a spring for urging said lever outwardly from said carriage, said spring and the pivot mounting of said lever constituting means for permitting said lever to disengage itself from said door if the moving door strikes an obstruction, and means for retracting said lever into said carriage against the tension of said spring when the carriage is in its normal position.

19. The combination with an elevator having a gate and which runs in a hatchway having a plurality of doors, of a door operator mechanism carried upon a unitary base, means for attaching said base on the top of the elevator to attach the operator thereto, a carriage on said mechanism, means for moving the carriage with respect to said base, a latch on each door, means on the carriage normally disengaged from said latches and moved into engagement with one of the latches by a movement of said carriage to thereby engage the operator mechanism with the door to move the same, and means connecting said carriage to said gate to cause the operator mechanism to move the gate simultaneously with said door, and checking means mounted upon said base and including a rotatable arm disposed in the path of movement of said carriage and engaged by said carriage to arrest the movement of the carriage door and gate.

JOSEPH C. TAMSITT.
